United States Patent Office

Des. 189,263
Patented Nov. 15, 1960

189,263

WEATHER INSTRUMENT OR SIMILAR ARTICLE

Jean O. Reinecke, Chicago, Ill., assignor to Airguide
Instrument Company, Chicago, Ill., a corporation of
Illinois

Filed Dec. 14, 1959, Ser. No. 58,649

Term of patent 14 years

(Cl. D52—7)

Fig. 1 is a front elevational view of a weather instrument or similar article, showing my new design;

Fig. 2 is a side elevational view thereof;

Fig. 3 is a top plan view thereof, and

Fig. 4 is a vertical section taken generally along the line 4—4 in Fig. 1.

The circular lines denote areas of contrasting color.

The dominant features of the design are shown in full lines.

I claim:

The ornamental design for a weather instrument or similar article, as shown and described.
